(57) **CLAIM**

The ornamental design for a display for a vehicle, as shown and described.

DESCRIPTION

FIG. 1 is a left side view of a display for a vehicle, showing our new design;

FIG. 2 is a front view thereof;

FIG. 3 is a right side view thereof;

FIG. 4 is a rear view thereof;

FIG. 5 is a top view thereof; and,

FIG. 6 is a right side perspective view thereof.

The long dash-short dash broken lines illustrating a boundary of the claim forms no part of the claimed design. The long dash-short dash broken lines depicting symbolic break lines form no part of the claimed design. Any portion of the article between the break lines form no part of the claimed design. The short dash broken lines depict portions of the display and form no part of the claimed design.
